UNITED STATES PATENT OFFICE

2,556,389

CONTAINER BRUSHING MACHINE

Arthur F. Darrah, Rochester, Vt.

Application August 3, 1949, Serial No. 108,285

3 Claims. (Cl. 15—72)

1

This invention relates to new and useful improvements in structural refinements in brushing machines for containers such as buckets, etc., and the principal object of the invention is to facilitate cleaning of the interior of such containers, particularly, the bottom of such containers, this being effected in a highly convenient, expeditious manner.

In particular, the instant invention concerns itself with certain improvements in the device which constitutes the subject matter of my co-pending application, Serial Number 56,796, filed on October 27, 1948, dealing generally with a device of this type. Thus, this application is a continuation-in-part of my earlier application above identified. However, while the device disclosed in my earlier application is well adapted for the purpose for which it is intended, I found that the same lends itself to certain improvements, particularly in the means for brushing the interior of the bottom of containers, and the primary feature of the apparatus herein disclosed, therefore, resides in the specific structural arrangement of my improved means for brushing the container bottom in such manner that the entire area of the bottom is contacted by the scrubbing brush unit.

Some of the advantages of the invention, as in my previous device, lie in its simplicity of construction, in its convenient and expeditious operation, and in its adaptability to use on containers of different sizes and types.

With the above more important objects and features in view and such other objects and features as may become apparent as this specification proceeds, the invention consists essentially of the arrangement and construction of parts as illustrated in the accompanying drawings, in which:

Figure 1 is a side elevational view of the invention;

Figure 2 is a cross sectional view, taken substantially in the plane of the line 2—2 in Figure 1, and, showing the brushes in their extended position;

Figure 3 is a cross sectional view, similar to that shown in Figure 2, but showing the brushes retracted;

Figure 4 is a cross sectional detail, taken substantially in the plane of the line 4—4 in Figure 2;

Figure 5 is a cross sectional view, taken substantially in the plane of line 5—5 in Figure 3;

Figure 6 is a perspective view of a brush holder used in the invention; and,

Figure 7 is a perspective view of one of the brush sections or members used therein.

2

Like characters of reference are employed to designate like parts in the specification and throughout the several views.

Referring now to the accompanying drawings in detail, the general reference character 10 designates a container brushing machine such as is generally disclosed in my aforesaid co-pending application, the same embodying in its construction a tube 12 which is rotatably mounted in a suitable bearing 14 and is rotated in any convenient manner.

A shaft 18 is slidably positioned in the tube 12, sliding thereof being effected by means of a pivoted lever 20 which operatively engages a bearing unit 22 provided with diametrically projecting trunnions 24, as is shown in Figure 1. That is to say, the trunnions 24 of the bearing 22 are disposed in suitable slots 26 formed in a forked end portion of the lever 20, so that by simply moving the lever from the position shown in full lines in Figure 1 to the position shown by the dotted lines 28, the shaft 18 may be slid in the tube 12 from left to right and vice versa.

Pairs of brackets 30 are welded or otherwise secured to an intermediate portion of the tube 12 and a set of bell cranks 32 are pivoted as at 34 to these brackets, the bell cranks 32 carrying at one end thereof suitable pivotally mounted brushes 36 adapted to scrub the inner surface of the side wall of the container, while the remaining ends of the bell cranks are operatively connected by means of pivoted links 38 to a pair of trunnions 40 which are provided at diametrically opposite sides of the shaft 18 and are slidable in longitudinally extending slots 42 with which the intermediate portion of the tube 12 is formed. It will be apparent from the foregoing that by simply imparting rotation to the tube 12 and sliding the shaft 18 so that the lever 20 occupies the position indicated at 28, the brushes 36 will be pressed outwardly from the tube 12 into engagement with the side wall of the container, the latter being indicated at 44.

The structure as above described is very similar to that disclosed in my earlier, co-pending application, and the instant invention deals with improved means for scrubbing the inner surface of the bottom 46 of the container 44, which means will now be described.

These means involve the provisions of a brush unit designated generally by the reference character 48, consisting of a channel-shaped holder 50, best shown in Figure 6, which has secured to the center portion thereof a cylindrical shank 52, slidable in and projectable outwardly from the free end portion of the aforementioned tube

12. To assure simultaneous rotation of the brush member 48 with the tube 12, a diametrically extending pin 54 is provided on the shank 18 and is slidable in a pair of slots 56 provided in the tube, while an additional pin 58 extends transversely of the tube and is slidable in a pair of slots 60 with which the shank 52 is formed. A compression spring 62 is positioned between the shank and the tube, one end of the spring bearing against the pin 54 while the remaining end thereof bears against the pin 58, whereby the brush assembly 48 is urged in engagement with the bottom 46 of the container 44.

The brush unit 48 also includes a pair of brush sections 64, equipped with individual, channel-shaped holders 66, which are juxtaposed and slidable in the holder 50, as will be clearly apparent. The holders 66 of the brush sections 64 are equipped with suitable studs 68 which are slidable in pairs of slots 70 with which the holder 50 is formed, the studs or screws 68 extending through the brush sections 64 as well as through the holders 66, 50, so that the brush sections are not only retained in position in the respective holders 66, but so that the brush sections, including the holders 66, are retained in position in the holder 50.

A pair of flexible cables 72 are connected at one end to the aforementioned trunnions 49, while the remaining end of each cable is connected to one of the studs 68 of the respective brush sections 64, it being noted that the cables 72 pass around suitable guide pulleys 76 which are mounted on the holder 50. These pulleys are so arranged that the cables 72 extend to opposite sides of the tube 12, it being apparent from the foregoing that when the apparatus is in operation and the shaft 18 is slid in the tube 12 so as to engage the brushes 36 with the side walls of the container, the cables 72 will be drawn in the direction of the arrow 78 (see Figure 1) and the brush sections 64 will be slid in relatively opposite directions, outwardly from the holder 50, so that they span the entire diameter of the container bottom 46.

However, means are provided for retracting the brush sections 64 after the lever 20 is actuated so as to draw the brushes 36 toward the tube 12, these last mentioned means consisting of a pair of tension springs 80, connected at one end to studs 68 of the brush sections, while the remaining ends of the springs are anchored on suitable posts or detents 82 with which the holder 50 is provided.

It is believed that the advantages and use of the invention will be clearly apparent from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

1. In a machine for brushing the interior of a cylindrical container, the combination of a rotatable tube, a plurality of outwardly and inwardly swingable levers pivoted to said tube, brushes mounted on said levers and adapted to engage the side wall of a container, a shaft slideable in said tube, trunnions secured to said shaft and projecting outwardly through longitudinally extending slots provided in said tube, links pivoted to said trunnions and to said levers whereby said brushes may be swung inwardly and outwardly by the sliding of said shaft, an additional brush unit adapted to engage the bottom of a container and comprising a channel-shaped holder mounted transversely at one end of said tube, a pair of juxtaposed brush sections slideable in opposite directions and projectable from opposite ends of said holder, resilient means for retracting said brush sections into the holder, and means responsive to the sliding of said shaft for projecting said brush sections.

2. The device as defined in claim 1 wherein said last mentioned means include guide pulleys mounted on said holder, and flexible elements passing around said pulleys and connected at one end to said brush sections, the remaining ends of said elements being connected to said trunnions.

3. The device as defined in claim 1 together with a spring pressed shank slideable in one end portion of said tube, said holder being mounted on said shank.

ARTHUR F. DARAH.
